Primary Examiner — Daniel J Domino*Assistant Examiner* — Samina Vieth(74) *Attorney, Agent, or Firm* — Lippes Mathias LLP(57) **CLAIM**The ornamental design for a radio frequency aperture, as
shown and described.**DESCRIPTION**FIG. 1 is a perspective view of the claimed design for a radio
frequency aperture; and,

FIG. 2 is a top plan view thereof.

The broken lines immediately adjacent to the claimed area
depict boundaries of the claimed design and form no part
thereof. The broken lines showing the remainder of the radio
frequency aperture depict environmental structure and form
no part of the claimed design.**1 Claim, 2 Drawing Sheets****FIG. 1**

FIG. 2
